UNITED STATES PATENT OFFICE

2,497,085

ARTILLERY TRAINER

Clayton H. Jeffers, Phoebus, Va.

Application October 5, 1945, Serial No. 620,615

6 Claims. (Cl. 35—25)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to an artillery trainer of the type in which an artillery weapon is simulated in construction and operation for the purpose of training artillery personnel in the function of loading such weapon.

The invention contemplates and has for its principal object the provision of a training device comprising means simulating a gun tube and breech mechanism having a breechblock mounted for opening and closing. The gun tube comprises a pair of separable sections from which the ammunition may be unloaded laterally instead of axially. The prime purpose for such training device is to provide an apparatus which simulates as closely as possible an actual artillery weapon so that the weapon itself is spared the wear and tear incident to simulated loading and firing functions. It will be appreciated that if a weapon itself is continually loaded and unloaded the breech mechanism thereof would be worn to the extent that it would be useless for actual firing. Furthermore, the weapon itself cannot be easily unloaded so that the ammunition can be successively loaded therewith.

According to the present invention the simulated gun tube comprises a pair of separable sections into which the ammunition may be loaded. When the breechblock is closed, the sections separate so that the ammunition may be easily unloaded therefrom and reloaded into the gun tube for successive cycles of operation.

An important object of the invention is to provide a training apparatus particularly useful in the handling of ammunition of the separate-loading type, in which the projectile and propelling charge are separate components.

The invention has for another object the provision of means comprising a base and a main frame mounted on the base for simulating elevation and depression of the gun tube.

A still further object of the invention is to provide means simulating a gun tube and including a portion adapted to retain the projectile until the propelling charge has been loaded and the breechblock closed, and to include means responsive to closing of the breechblock for releasing the projectile and propelling charge to a position from which those components may be readily removed and returned to the gun crew for further simulated loading.

The foregoing and other objects and features

2

of the invention will become apparent as the disclosure is more fully made in the following detailed description and accompanying sheets of drawings in which:

5 Fig. 1 is a side elevational view of a preferred form of the training apparatus, the position of the separable gun tube being indicated in broken lines;

Fig. 2 is a plan view of the same;

10 Fig. 3 is a rear or breech-end view of the same; Fig. 4 is a longitudinal sectional view, on an enlarged scale, of the gun tube and breech mechanism construction, the view being taken along the line 4—4 of Fig. 2;

15 Fig. 5 is a fragmentary plan view of the rear or breech-end portion of the apparatus showing the structure and function of the breechblock in connection with the means for releasing the separable sections of the gun tube;

20 Fig. 6 is a fragmentary side elevational view showing the means providing for simulated elevation of the apparatus;

Fig. 7 is a rear end elevation of the projectile-receiving portion of the simulated gun tube;

25 Fig. 8 is a rear end elevation of the lower portion of the simulated gun tube; and

Fig. 9 is a rear end elevation of the upper section of the simulated gun tube.

The particular embodiment of the invention 30 chosen for the purposes of illustration herein comprises a generally horizontal base 10 including a pair of longitudinally running converging side frame members 11 rigidly cross connected at their forward ends by a transverse horizontal

35 plate 12 and rigidly cross connected at their rear ends by a transverse bar 13. The forward end of the base 10 includes a pair of transversely spaced upright plates 14, each of which is provided with a plurality of openings 15 formed on

40 a transverse axis. The components just described are preferably rigidly secured together as by welding.

The base 10 serves to support a main frame indicated in general by the reference numeral 45 16. This main frame comprises a pair of forwardly converging longitudinally running lower side frame members 17; a pair of forward vertical uprights 18; a pair of upwardly converging frame members 19; and a pair of transversely spaced, forwardly and downwardly inclined bracing members 20. The rear frame members 19 are rigidly cross connected by a transverse vertical

50 plate 21, the upper portion of which is arcuately cut out to receive and conform to means simulating a gun tube of a standard artillery weapon.

This means is indicated generally in the drawings by the numeral 22 and comprises a rear portion having an upper section 23 and a lower section 24. The rear portion of the gun tube further includes structure simulating breech mechanism, as indicated generally at 25. The breech mechanism includes a circular breech ring 26 and a breechblock 27. The breechblock is pivoted on a vertical axis 28 for opening and closing. The interior of the breechblock is herein shown as the interrupted screw type and is provided with an operating handle 29 for opening and closing the breechblock. The upper section 23 of the gun tube 22 is substantially cylindrical and tubular at its rear end, as at 30, and its forward portion is semicylindrical in cross section as at 31 (Fig. 9). The cylindrical rearward portion of the section 23 has rigidly secured thereto, as by welding, a circular flange 31a. This flange is rigidly secured, as by bolts 32, to the front face of the breech mechanism 25. The longitudinal axis of the section 23 is, of course, coincident with the longitudinal axis of the interior of the breech mechanism. The breech mechanism is rigidly carried by the upper portion of the main frame 16, through the medium of the rear uprights 19, the brace members 20, and the transverse plate 21. The forward end of the section 23 is rigidly carried by the upper portions of the front uprights 18, a transverse supporting member 33 rigidly cross connecting the uprights 18 and being secured to the forward end of the section 23. A pair of transversely spaced, forwardly converging reinforcing ribs or wings 34 is provided on the external semicylindrical surface of the section 23.

The upper section 23 of the gun tube is provided at its rear end with a pair of closely transversely spaced depending ears 35 transversely bored to receive a pivot pin 36. The lower section 24 of the gun tube is provided at its rear end with a pair of complementary ears 37 transversely bored to receive the pin 36. This structure provides means by which the lower section is pivotally carried by the upper section for vertical swinging movement. In other words, the lower section is downwardly separable from the upper section. The forward end of the upper section is provided with a transversely extending stub shaft 38 comprising part of a bracket 39 rigidly secured, as by welding, to the upper section 23. The lower section carries rigidly thereon at a point below the bracket 39 a hook or latch member 40. An arm 41 is rockably carried by the stub shaft 38 and has a lower hooked portion which normally engages the under portion of the latch member 40. The upper end of the arm 41 is pivotally connected to a clevis 42 carried at the end of a longitudinally running rod 43. An intermediate portion of the upper section 23 of the gun tube is provided with a laterally extending integrally formed bracket 44 which has an upstanding supporting portion 45. The portion 45 is provided with a transversely inwardly extending apertured ear 46 through which the operating rod 43 passes. The circular plate at the rear end of the breech mechanism 25 is bored longitudinally as at 47 and slidably receives the rear end of the rod 43. The rod 43 carries thereon, at a point rearwardly of the apertured ear 46, a stop collar 48. A coiled compression spring 49 is interposed between the forward face of the collar 48 and the rearward face of the apertured ear 46. The action of the spring is such that extension thereof urges the rod rearwardly with the result that when the breechblock is open the rearward portion of the

rod 43 projects through the bore 47 in the breech ring 23 and maintains engagement of the arm 41 with the hook 40 on the lower gun tube section 24 (Fig. 5). Thus, when the breechblock 27 is closed, it will engage the projecting end of the rod 43 and will move the rod forwardly against tension of the spring 49. This action will swing the arm 41 in a clockwise direction as seen in Figure 1 and will release the hooked lower end thereof from the latch member 40 on the gun tube section 24.

As previously stated, the trainer herein illustrated is adapted primarily for use in training battery personnel in the loading of ammunition of the type comprising a projectile and a separate propelling charge. The apparatus is therefore provided with a forward extension member 50 having semicircular shape and being rigidly carried at one end by the main frame members 18 and 33 in axial alignment with, and in effect a longitudinal continuation of, the upper gun tube section 23. The extension member 50 is provided with a pair of upper forwardly converging reinforcing ribs or wings 51 and has at its extreme forward end a circular end member 52. The end member carries at its inner face a stop pad 53. This pad may be formed of any suitable material, such as soft metal, rubber or the like, and serves as a shock-absorbing element against which a projectile may abut when rammed axially into and through the gun chamber 22. When the gun tube, which includes the forward extension 50 as part thereof, is loaded with the two components of a round of separate-loading ammunition, the projectile, herein designated by the numeral 54, enters the forward extension 50 and the powder bag containing the propelling charge, herein designated by the numeral 55, is carried by the lower section 24 and is contained within the separable lower and upper sections.

The forward portions of the upper and lower sections 23 and 24 respectively carry complementary halves of separable jaw sections 56 and 57 for gripping the rear end of the projectile 54. The jaw sections are interiorly tapered so that the projectile is guided therethrough and into the forward extension 50. When the lower section 24 is latched in normal position by the arm 41, the jaws 56 and 57 prevent the projectile 54 from dropping downwardly through the open underside of the forward extension 50. When the breechblock 27 is closed, the rod 43 is actuated to release the latch arm 41 and the lower gun tube section 24 swings downwardly. The projectile 54 is released to drop by gravity to a tray 58 rigidly carried by the forward end of the main frame 16 and appropriately supported as by brace members 59. The tray 58 is further supported by a forward plate 60 secured at its lower end to the tray and secured at its upper end to the end member 52 of the forward extension 50. A shield 61 is positioned at one side of the tray 58 to confine the dropping projectile against improper discharge. The tray 58 slopes slightly to the left so that ready access may be had to the dropped projectile. The rearward end of the tray 58 projects, as at 62, to provide stop means for limiting downward swinging of the lower gun tube section 24 when it separates from the upper gun tube section 23. The tray 58 is provided with suitable padding as at 63 for absorbing the shock of the falling projectile.

The transverse bar 13, previously described as rigidly cross-connecting the rear ends of the base frame members 11, serves as a pivot by means of

which the main frame 16 is mounted on the base 10 for vertical swinging about a transverse axis. A transverse rod 64 is passed through transversely aligned apertures in the forward ends of the frame members 17 and through the lower apertures 15 in the upright plates 14 when the apparatus is set at zero elevation. As shown in Fig. 6, the main frame may be elevated to either of two positions, in which case the transverse rod 64 is optionally received by the upper or intermediate apertures 15 in the plates 14.

The preferred form of invention herein disclosed includes means for returning the lower gun tube section 24 to normal position after it has been released by closing of the breechblock 27. In the present instance this means takes the form of a counter-weight 65 suspended at one end of a cable 66. The cable is trained over a sheave or pulley 67 rotatably carried on a bracket 68 at one side of the upper transverse frame member 33. The other end of the cable 66 is anchored in a bracket 69 carried rigidly at the proximate side of the lower gun tube section 24.

The apparatus includes counterbalance means for the breechblock 27. The upper end of the supporting post or portion 45 is provided with a vertical pivot 70 on which is carried a cylinder 71, the forward end of the cylinder being provided with an appropriate bracket 72 for pivotal mounting on the pivot 70. The cylinder contains a suitable counterbalance mechanism, preferably of the spring and plunger type, and has a rearwardly extending piston rod 73 formed with a clevis 74. The clevis is connected by a vertical pivot 75 to a block 76 adjustably carried in a normally transversely extending slot in a bracket 77. An adjusting bolt 78 is carried by the bracket 77 and is threaded through the block 76 so that the position of the block may be varied in the slot in the bracket. The bracket 77 is carried at the upper end of an upper extension 19 of the breechblock pivot 28 and is so mounted that it swings when the breechblock is opened and closed (Figs. 2 and 5). When the breechblock is opened it assumes the position shown in Fig. 5, in which instance relationship between the cylinder 71 and pivots 70, 75 and 79 is such to provide an over-center lock that will maintain the breechblock in open position. When the breechblock is moved initially toward closing, the action of the counterbalance mechanism will assist in the closing operation and will further serve to keep the breechblock closed.

Operation

In the use of the trainer for the purpose of instructing battery personnel in the fundamentals of loading an artillery weapon, the main frame 16 is set at the desired elevation on the base 10, this result being accomplished by means of the adjustment provided by the transverse openings 15 in the upright plates 14 and the transverse supporting rod 64 at the front ends of the lower main frame members 17. When the breechblock 27 is swung open, the compression spring 49 on the release rod 43 will act against the collar 48 to project the rear end of the rod 43 through the breech ring 26 (Fig. 5). This action will lock the latch arm 41 under the hook member 40 and will hold the lower gun tube section 24 against dropping downwardly. It will be understood of course that, in the absence of ammunition in the gun chamber, the counterweight 65 will hold the lower section against separation. The action of the counter-balance mechanism in the cylinder 71 will keep the breechblock in its open position.

The ammunition used in the simulated loading operation is preferably composed of dummy components and in the present instance is of the separate-loading type in which the projectile 54 is separate from the powder bag 55. The projectile 54 is loaded through the open breech and is rammed forwardly until it occupies the position in Fig. 4. The buffer member 53 at the forward end of the extension 50 will stop the projectile and the rear end portion of the projectile will be retained by the complementary half rings 56 and 57 carried by the upper and lower gun tube sections 23 and 24 respectively. The powder bag 55 will then be loaded into the gun tube. When the breechblock is slammed shut it will force the release rod 43 forwardly and will pivot the latch arm 41 out of engagement with the hook member 40, allowing the lower gun tube section 24 to drop to the position shown in broken lines in Fig. 1. The weights of the projectile and powder bag are sufficient to overcome the counterweight 65. The projectile 54 will, of course, drop downwardly and will be caught by the tray 58. The padding material 63 will serve to absorb the shock of the dropping projectile.

At the same time the lower gun tube section will have moved to its downwardly tilted position, the movement thereof being braked somewhat by action of the counterweight 65. Other battery trainees may then unload the projectile 54 and powder bag 55 from the tray 58 and lower gun tube section 24, respectively, so that another round may be loaded into the simulated gun tube after the lower gun tube section, having been relieved of the weight of the powder bag 55, returns to normal position. It is probably preferable that a separate crew be provided for the sole purpose of unloading the ammunition dropped after the breechblock is closed. This procedure will permit loading personnel to continue loading as rapidly as possible.

One of the most important features of the preferred embodiment of the invention herein illustrated and described is that unloading of the rounds of ammunition may take place in a direction transverse to the longitudinal axis of the gun tube structure. It will be appreciated that the ability of the trainer to function in this manner is far more desirable than structure in which axial unloading is required. Other features of perhaps greater or lesser importance will appear to those skilled in the art. It will be understood, of course, that the foregoing description and drawings pertain to only a preferred embodiment of the invention and that various modifications and alterations may be made therein without departing from the spirit and scope of the invention as defined in the appended claims.

60 What is claimed is:

1. An artillery trainer for use with ammunition of the type having a projectile and a separate propelling charge, comprising a generally horizontal base, a main frame mounted on said base, means simulating a generally horizontal longitudinal gun chamber at an upper portion of said main frame said means including a generally semi-cylindrical upper section and a generally semi-cylindrical lower section, means rigidly mounting said upper section on said main frame, means pivotally mounting said lower section on said upper section for pivoting downwardly from said upper section about a generally horizontal transverse axis at the rear end of said lower section to provide for removal of the propelling

charge therefrom, means including a releasable latch normally holding said lower section in cooperating chamber-forming relation with said upper section, means forming a generally longitudinal extension on said upper section for housing the ammunition projectile, there being an opening in the under side of said extension through which said projectile may drop, cooperating means on said sections for gripping the projectile to retain the same in position in said extension until said lower section is released for downward tilting, means on said main frame below said extension for catching the projectile when dropped, means simulating breech mechanism associated with said gun chamber and including a breechblock mounted for opening and closing, means operable in response to closing of said breechblock for releasing said latch to thereby release said lower section from said upper section, and means including a counterweight for returning said lower section to normal position upon the unloading of ammunition therefrom.

2. In an artillery training device, a frame, an upper, generally horizontal semi-cylindrical member fixed in said frame, a lower semi-cylindrical member pivoted at its rear end to said upper member on a normally horizontal transverse axis and pivotable downwardly from a first position closed against said upper section, to a second downwardly and forwardly inclined position, said lower member when in first position, cooperating with said upper section to form a cylindrical gun chamber, and when in second position forming a downwardly and forwardly directed chute, said lower section when in first position coacting with said upper section to grip a projectile at their forward ends, a breechblock pivoted on said frame rearwardly of and aligned with said sections, releasable latch means normally holding said lower section in first position, and means releasing said latch means in response to movement of said breechblock to closed position.

3. An artillery trainer for use with ammunition of the type having a projectile and a separate propelling charge, comprising a base, a main frame mounted on said base, means simulating a generally horizontal longitudinal gun chamber on said main frame and including an upper section and a separable lower section adapted to receive the ammunition propelling charge, means rigidly mounting said upper section on said main frame, means mounting said lower section on said upper section for separation downwardly from said upper section, means including a releasable latch normally holding said sections together, means forming a generally longitudinal extension on said upper section for receiving a projectile, means forming an opening in the under side of said extension through which said projectile may drop, jaw means carried by the forward ends of the respective sections and cooperable between said sections for retaining of the projectile within said extension, said jaw means releasing said projectile when said lower section is released, means simulating breech mechanism associated with said gun chamber and including a breechblock mounted for opening

and closing, means operable in response to closing of said breechblock for releasing said latch to free said lower section from said upper section, and means including a counterweight for returning said lower section to normal position upon the unloading of ammunition by gravity therefrom.

4. In an artillery training device, a frame, an upper chamber section fixedly carried by said frame, said upper section being generally semi-circular in cross section, a lower section pivoted to said upper section, at the rear end thereof, on a normally horizontal axis transversely of said sections, said sections cooperating to form a powder chamber when said lower section is closed against said upper section, a releasable latch operable in one position to hold said lower section in chamber-forming position and in a second position to release said lower section and permit the same to pivot downwardly in response to gravity, to discharge a powder bag therefrom, said sections having cooperating jaws at their forward ends to grip and hold a projectile therebetween only when said lower section is in chamber-forming position, a breechblock carried by said frame and movable to open and close the rear end of said chamber, and means responsive to movement of said breechblock to closed position to move said releasable latch to second position.

5. In an artillery trainer, means comprising upper and lower sections, said lower section being pivoted at its rear end to said upper section, upon a normally horizontal axis transverse to said sections, said sections cooperating to form a powder-receiving chamber when said lower section is pivoted upwardly into closed position with respect to said upper section, the forward ends of said sections cooperating to grip and support a projectile therebetween when said sections are in chamber-forming relation, and latch means releasably holding said sections in chamber-forming relation.

6. In a device as recited in claim 2, and a chute carried by said frame and forming a downwardly and forwardly directed continuation of said lower section when the latter is in second position, whereby a simulated projectile and propelling charge loaded into said device, are conveyed to a common location forwardly of the device on closure of said breechblock.
